WALTER FERRIS, OF SOUTH MILWAUKEE, WISCONSIN, ASSIGNOR TO
THE BUCYRUS COMPANY, OF SOUTH MILWAUKEE, WISCONSIN, A
CORPORATION OF WISCONSIN.

EXCAVATING MACHINERY.

No. 836,249.

Specification of Letters Patent.

Patented Nov. 20, 1906.

Application filed October 6, 1905. Serial No. 281,694.

To all whom it may concern:

Be it known that I, WALTER FERRIS, a citizen of the United States, residing at South Milwaukee, county of Milwaukee, State of Wisconsin, have invented certain new and useful Improvements in Excavating Machinery; and I do hereby declare the following to be a full, clear, and exact description of the invention, such as will enable others skilled in the art to which it appertains to make and use the same.

The invention relates to excavating machinery, and more particularly to dipper-excavators, and has for its object to improve and simplify the mechanism for operating the dipper and for supporting the boom, to the end that the severe twisting and torsional strains to which apparatus of this character is subjected will be in a large measure avoided, whereby efficient operation of the machine will be insured under all conditions of service and the wear and tear on the various machine parts will be materially reduced.

In the accompanying drawings, Figure 1 is a side elevation of the forward part of an excavator embodying the principles of my invention. Fig. 2 is a plan view thereof. Figs. 3 and 4 are a plan view and a side elevation, respectively, of the improved form of dipper-handle.

In the ordinary excavator, particularly those of the steam-shovel type, the hoisting-gear pulls directly on the middle of the dipper due to its attachment to the bail or handle with which the dipper is supplied. In forcing the dipper up through the bank in which the cut is being made if one corner of the dipper or one of the teeth located to one side of the axis line strikes a rock or other obstruction while the rest of the bank is soft, the strain is shifted far over to one side of the center line, and a severe twisting action is set up in the dipper-handle. More or less of this twisting action is going on at all times in ordinary steam-shovel work, and it is a matter of common knowledge that it causes a great deal of breakage of dipper-handles and rapid wearing of thrusting-pinions, saddle-blocks, and other appurtenant parts of the dipper-

operating mechanism. Furthermore, in the ordinary swinging operation of the boom as the dipper is being moved back and forth from the cut a considerable reaction or drag, due to the inertia of the dipper, is set up, 55 which tends to pry apart the ordinary form of boom through which the dipper-handle passes. Furthermore, in the usual form of excavator the guy rods or supports for the boom extending from the outer end of the 60 boom to the collar on the A-frame are arranged parallel with each other, so that if the boom receives an excessive load at one side near the upper end the tendency of the boom-guy on that side to receive and sustain such 65 load, more or less, results in the strain being delivered, by means of the A-frame collar as an equalizer, to the other boom-guy, and the unequal load is eventually resisted by the torsional strength of the boom itself twisting or reacting against the foot-sockets, 70 which not infrequently results in badly deforming or even rupturing the boom or its supports.

The object of the present invention is to 75 obviate these various difficulties; and the invention, in its broadest aspects consists in sustaining the dipper from two widely-separated points by means of separate cables, which are taken in at the same rate of speed 80 without regard to the load carried by each, preferably constructing the dipper-handle of two parallel sections or bars, which straddle the boom and coöperate with separate thrusting-pinions on each side of the boom, and in 85 providing a set of guys or supports for the excavator boom, extending from the boom to the A-frame collar, and so arranged as to prevent equalization of the loads delivered to the boom-guys through the A-frame collar. 90

In the embodiment of the invention illustrated in the drawings, *a* indicates the car-body upon which the steam-shovel excavator is supported and from which the dipper is operated in the usual well-known manner. 95 Pivotally mounted upon the front of the car-body is the boom *b*, which supports the dipper and the operating mechanism therefor.

The dipper *c*, which is of the usual form, having a hinged bottom and provided with 100

digging-teeth on its front edge, is supported by a handle, which latter consists of two parallel bars or sections *c*, connected at the lower end by a spacer *c'* and passing on opposite sides of the boom *b* through a saddle-block *e*, mounted upon the boom. Each section of the dipper-handle is provided on its lower face with a rack *d*, which co-operates with thrusting-pinions *f*, mounted upon a shipper-shaft *f'*, which in turn is mounted upon the upper side of the boom. Rotatory motion is imparted to the thrusting-pinions *f* by means of gear-wheels *g*, either connected directly to said thrusting-pinions or attached 15 to the shaft upon which the pinions may be mounted, and the respective gears *g* are driven by means of gears *h* on the crank-shaft of the engine *i*, mounted on the boom. This construction of divided dipper-handle 20 permits a continuous undivided boom to be employed, thereby omitting the usual slot in the boom, through which the dipper-handle passes in the ordinary type of excavator, which slot greatly weakens the boom without 25 in any way strengthening the dipper-handle, and also affords a very undesirable connection between the dipper-handle and the boom, which tends to cause the former to pry the boom apart when the handle is subjected 30 to the lateral strains incident to the ordinary operation of the machine. This tendency of the dipper-handle to pry open the divided boom, as heretofore employed, is particularly noticeable when the boom is being 35 swung from side to side, and the inertia of the dipper and its handle causes one side of the latter to engage the lower edge of the boom, while the other side of the undivided handle comes in contact with the upper in- 40 side edge of the boom, thereby producing all of the effects of a powerful lever tending to split the boom apart. By employing the divided dipper-handle, which straddles the boom and engages separate thrusting-pin- 45 ions overhanging the sides of the boom, the force required to accelerate the dipper in starting or stopping the swinging movement of the boom and dipper is communicated by a push and pull upon the respective thrust- 50 ing-pinions, which is dissipated without injurious effect upon any of the parts.

Connected to widely-separated points on the dipper, and preferably to suitable eyes or yokes *m*, attached near the upper rear corners thereof, are two separate suspending-cables *n n'*, by means of which the dipper is raised and lowered—that is to say, the cables *n n'* are drawn out by the fall of the dipper when the latter is permitted to move into 55 position to take a fresh cut and are taken in to force the dipper into the bank and also to lift the dipper in the digging operation. It will be evident that if the suspending-cables 60

n n', which may, of course, be in the form of ropes, chains, or any other flexible connecting means, are taken in at the same rate of speed during the digging operation of the dipper, each cable will normally support its proper proportion of the load; but should any unequal loading of the dipper occur—as, 65 for example, when it strikes a heavy stone or other obstruction in passing upward through the bank—the division of the hoisting-strain between the two cables is immediately shifted, and the particular cable which is attached to the side of the bucket upon which the strain is imposed receives practically all the load, while the other cable is correspondingly relieved of strain. The effect of this arrangement is to practically protect the dipper-handle from torsional stress and to 70 throw the whole of said torsional stress into the boom by way of the hoisting-gear instead of through the dipper-handle, as is usually done in the ordinary arrangement of 75 boom and dipper-handle.

Any suitable mechanism may be employed for taking in the cables *n n'* during the digging operation—such, for example, as a single winding-drum on the car-body or other support for the excavator, to which winding-drum the cables *n n'* are led over the boom through a suitably-arranged fair-lead at the foot of the boom or by placing the winding drum or drums on the boom, and if two drums are employed driving the same at the same rate of speed, so that both of said cables will be taken in at the same uniform rate. In the form of the invention illustrated, which is only one of many possible 90 arrangements of hoisting apparatus within contemplation of this invention, two winding-drums *o o'* are mounted upon a shaft *p*, journaled on the outer end of the boom, said drums being of the same size and each having an end of the corresponding cables *n n'* secured thereto, so that as said drums are rotated the cables *n n'* will be wound upon the respective drums at the same rate of speed. A simple and effective mode of driving the 95 drums *o o'* at the same rate of speed consists of a cable *r*, which is wound in an opposite direction upon a hoisting-drum *q*, preferably of considerably larger diameter than the said winding-drums, said drum *q* being fast to the shaft *p*, upon which drums *o o'* are secured. The cable *r* is led along the boom and under an appropriate fair-lead *s* to the power-drum on the car-body. It will be noted that this arrangement of the two winding-drums of 100 smaller diameter than the hoisting-drum *q*, constitutes a differential drum, which enables the speed of operation of the bucket to be materially increased without increasing the number of transmission-gears and without 105 imposing heavy weights on the boom.

Should it be found desirable, the drums o , o' , and q , forming the differential drum, may be located on the boom below the shipper-shaft and the cables n n' led over suitable 5 guide-pulleys on the end of the boom. Furthermore, it is feasible to dispense with the drum q and operate the shaft p by means of suitable gearing, mounted in part upon said shaft p and in part upon a power-shaft running longitudinally of the boom. Under certain conditions, a sprocket-and-chain drive 10 may be substituted for the drum q and the cable r , and in fact any appropriate means for imparting the same speed of rotation to the drums o o' , wherever the same may be located, is within the purview of the present invention.

In order to relieve the boom itself from a large proportion of the torsional strains 15 which would otherwise result from this new arrangement of hoisting-gear, as well as from the forms of hoisting-gear heretofore in use, there is provided a special form and arrangement of boom-guys, which serve to so distribute the load that it is taken up by the **A**-frame without imposing torsional strains 20 upon the boom. In the ordinary arrangement of boom-guys the two guy-rods are arranged in parallel relation on each side of the boom and are connected at their ends to the outer end of the boom and to lugs on either side of the **A**-frame collar. With this system of supporting the boom if the latter receives an excessive load at one side near the upper 25 end the guy on that side transmits the strain, by means of the **A**-frame collar as an equalizer, to the boom-guy on the other side, and the ultimate strain is evidenced as a torsional or twisting effect in the boom, which is to be resisted by the strength of the boom itself or by the thrust against the foot-sockets of the boom. To obviate this difficulty and to relieve the boom of twisting strains, according 30 to the present invention the guy-rods connected to the boom and **A**-frame are made divergent, so that the **A**-frame collar will not be made to serve as an equalizer of the loads delivered to them at their points of attachment to the boom. One form of this improved arrangement of guy-rods is illustrated 35 in the drawings, in which u u indicate the usual form of parallel guy-rods, each attached at one end to the end of the boom and at the other to the side of the collar v of the **A**-frame t . Connected to the same points on the boom end and the **A**-frame collar are diagonal guy-rods w , preferably formed of 40 separate links and connected to a cross-bar y , which joins the sections of the parallel guys u at their middle points. By this diagonal arrangement of boom-guys it will be apparent that a load imposed at one point of attachment of either rod to the boom end will be

transmitted to and equally divided between the two ends of the **A**-frame collar, so that 45 the latter will not turn under the strain and transmit the strain in the opposite direction to the other side of the boom. By this means when the boom receives an excessive stress on one side that side is supported and the 50 torsional strain of the boom is largely or entirely obviated, while the load is transmitted to the **A**-frame, which is intended to receive the same.

Having thus described my invention, what 55 I claim, and desire to secure by Letters Patent, is—

1. In an excavator, the combination of a boom-supported dipper, suspending-cables connected to said dipper at two points, and 60 means for taking in said cables at the same rate of speed; whereby the dipper is prevented from twisting under unevenly-distributed stresses.

2. In an excavator, the combination of a 65 boom-supported dipper, separate suspending-cables connected to said dipper near the upper rear corners thereof, and means for taking in said cables at the same rate of speed; whereby the dipper is prevented from twisting 70 under unevenly-distributed stresses.

3. In an excavator, the combination of a boom-supported dipper, suspending-cables connected to said dipper at two points, and 75 winding mechanism for taking in said cables at the same rate of speed; whereby the dipper is prevented from twisting under unevenly-distributed stresses.

4. In an excavator, the combination of a boom-supported dipper, suspending-cables 80 connected to said dipper at two points, winding-drums for the respective suspending-cables, and means for operating said drums at the same rate of speed.

5. In an excavator, the combination of a 85 boom-supported dipper, suspending-cables connected to said dipper at two points, winding-drums for the respective suspending-cables, and a power-drum connected to said winding-drums for operating the latter at the 90 same rate of speed.

6. In an excavator, the combination of a boom-supported dipper, suspending-cables connected to said dipper at two points, winding-drums for the respective cables, and a 95 power-drum for operating the latter at the same rate of speed, the said drums being mounted upon the boom.

7. Hoisting-gear for operating a boom-supported excavating-dipper, comprising a single hoisting-cable, two suspending-cables 100 running from separate points of connection with the dipper to the boom, and means for operatively connecting the hoisting-cable and the two suspending-cables.

8. Hoisting-gear for operating a boom-sup-

- ported excavating-dipper, comprising a single hoisting-cable, two suspending-cables running from separate points of connection with the dipper to the boom, and means on 5 the boom for operatively connecting the hoisting-cable and the two suspending-cables.
9. In an excavator, the combination of a dipper, suspending-cables connected to said dipper at two points, winding-drums for the 10 respective suspending-cables, and a hoisting-drum operatively connected to said winding-drums for driving the latter at the same rate of speed.
15. 10. In an excavator, the combination of a dipper, suspending-cables connected to said dipper at two points, winding-drums for the 20 respective suspending-cables, and a hoisting-drum operatively connected to said winding-drums for driving the latter at the same rate of speed, said hoisting-drum being of larger diameter than the winding-drums.
25. 11. In an excavator, the combination of a boom-supported dipper, suspending-cables connected to said dipper at two points, winding-drums for the 30 respective suspending-cables mounted upon the boom at a point beyond the foot thereof, a hoisting-drum operatively connected to said winding-drums for driving the latter at the same rate of speed, and a cable connecting the hoisting-drum with a source of power.
35. 12. In an excavator, the combination of a boom-supported dipper, suspending-cables connected to said dipper at two points, a shaft supported near the end of the boom, winding-drums for the respective suspending-cables on said shaft, a hoisting-drum on 40 said shaft, a cable connected with said hoisting-drum and running along said boom, and a fair-lead at the foot of said boom for directing said cable to a power-drum.
45. 13. In an excavator, the combination of a boom, a saddle-block revoluble about a shaft or pivot attached to said boom, and a dipper-handle, comprising two bars or sections parallel to each other, coöperating with said saddle-block and straddling the boom.
50. 14. In an excavator, the combination of a boom, a saddle-block revoluble about a shaft or pivot attached to said boom, pinions carried by said shaft or pivot and overhanging the edges of the boom, and a dipper-handle comprising two parallel bars or sections 55 straddling the boom and engaging the respective pinions.
60. 15. In an excavator, the combination of a boom, a saddle-block revoluble about a shaft or pivot attached to said boom, a dipper-handle, comprising two bars or sections parallel to each other, coöperating with said saddle-block and straddling the boom, a dipper supported by said handle, suspending-cables
- connected to said dipper at two points, and means for taking in said cables at the same 65 rate of speed.
16. In an excavator, the combination of a boom, having a saddle-block thereon, a dipper-handle, comprising two bars or sections parallel to each other, coöperating with said 70 saddle-block and straddling the boom, a dipper supported by said handle, suspending-cables connected to said dipper at two points, winding-drums for the respective suspending-cables, and means for operating said winding-drums at the same rate of speed. 75
17. In an excavator, the combination of a boom, having a saddle-block thereon, a dipper-handle, comprising two bars or sections parallel to each other, coöperating with said 80 saddle-block and straddling the boom, a dipper supported by said handle, suspending-cables connected to said dipper at two points, winding-drums on said boom for the respective suspending-cables, and means for operating said winding-drums at the same rate of speed. 85
18. In an excavator, the combination of a boom, a dipper-handle formed of parallel sections straddling the boom, a dipper supported by said handle, suspending-cables connected to said dipper at two points, winding-drums for the respective cables, and means for operating said winding-drums at the same rate of speed. 90
19. In an excavator, the combination of a boom, a dipper-handle formed of parallel sections straddling the boom, a dipper supported by said handle, suspending-cables connected to said dipper at two points, winding-drums for the respective cables, a hoisting-drum operatively connected to said winding-drums for driving the latter at the same rate of speed, and a hoisting-cable for operating said hoisting-drum. 95
20. In an excavator, the combination of a boom-supported dipper, and means for operating said dipper, comprising three drums, cables extending from two points on the dipper to two of said drums, and a cable extending from the third drum to the hoisting mechanism. 100
21. In an excavator, the combination of a boom-supported dipper, and means for operating said dipper, comprising three drums located on the boom, cables extending from two points on the dipper to two of said drums, and a cable extending from the third drum to the hoisting mechanism. 115
22. In an excavator, the combination of a boom, an A-frame mounted near the foot thereof, and divergent guy-rods connecting the boom and the A-frame collar. 120
23. In an excavator, the combination of a boom, an A-frame mounted near the foot thereof, and diagonal guy-rods attached at 125

widely-separated points on the boom and **A**-frame collar respectively.

24. In an excavator, the combination of a boom, an **A**-frame mounted near the foot thereof, and diagonal guy-rods connected substantially at their middle and attached to diagonally opposite points on the boom and **A**-frame collar respectively.

25. In an excavator, the combination of a boom, an **A**-frame mounted near the foot thereof, parallel guy-rods extending from the

ends of the boom to the **A**-frame collar, and diagonal guy-rods connecting diagonally opposite points on the boom and **A**-frame collar respectively.

In testimony whereof I affix my signature in presence of two witnesses.

WALTER FERRIS.
